CLAIM

The ornamental design for a nozzle for vacuum cleaner, as shown and described.

DESCRIPTION

FIG. 1 is a front perspective view of the nozzle for vacuum cleaner showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a bottom perspective view thereof;

FIG. 9 is a bottom perspective view showing the use state that a damp cloth has been attached to the wet cleaning part on the bottom; and,

FIG. 10 is a front perspective view showing the use state that the claimed design has been attached to the body for vacuum cleaner.

The broken lines depict portions of the nozzle for vacuum cleaner that form no part of the claimed design. The portions of FIGS. 9 and 10 drawn in broken lines show environmental structure only and form no part of the claimed design.
